[57] **CLAIM**

The ornamental design for a base support mount for a heat pump or the like, as shown and described.

DESCRIPTION

FIG. 1 is a perspective view of a base support mount for a heat pump or the like showing our new design;

FIG. 2 is a side elevational view thereof;

FIG. 3 is a bottom plan view thereof;

FIG. 4 is a top plan view thereof; and

FIG. 5 is a perspective view of a modified form of the base support mount described in FIG. 1 showing our new design.

The base support mount of FIG. 5 shows the center cylinder wall broken away to show indeterminate length.

The bottom plan and top plan views of FIG. 5 are identical with FIGS. 3 and 4, respectively.

FIG. 1

FIG. 2

FIG. 3

FIG. 4

FIG. 5
